UNITED STATES PATENT OFFICE.

JOSEPH COURVILLE, OF DETROIT, MICHIGAN.

MECHANICAL PIANO-PLAYER.

1,018,167.

Specification of Letters Patent. Patented Feb. 20, 1912.

Application filed April 15, 1910. Serial No. 555,577.

To all whom it may concern:

Be it known that I, JOSEPH COURVILLE, a citizen of the United States, residing at Detroit, county of Wayne, State of Michigan, have invented a certain new and useful Improvement in Mechanical Piano-Players, and declare the following to be a full, clear, and exact description of the same, such as will enable others skilled in the art to which it pertains to make and use the same, reference being had to the accompanying drawings, which form a part of this specification.

My invention relates to mechanical piano players and the object of my improvements is to provide an apparatus for passing the music sheet over the tracker board and one that shall more accurately locate the music sheet and direct its course. I secure this object in the device illustrated in the accompanying drawing, in which,

Figure 1, is a section of an apparatus embodying my invention. Fig. 2, is a front elevation of the same, a part of the music sheet being cut away to show the tracker board. Fig. 3, is a detail view partly in section.

A, indicates the framework for supporting the rolls.

B, is the music roll and C, the roll upon which the music sheet passes from the music roll.

D, is the tracker board and F, is the music sheet. The sheet F passes from the music roll B over the tracker board D and onto the roll C.

E, is an auxiliary roller formed with a greater diameter toward its center and tapering toward both ends having guiding flanges E¹, E¹, at its ends and located between the music roll B and the tracker board D so that the music sheet F shall be bent inward between the roll and the tracker board, as indicated in Fig. 1.

e, e, are pintles extending from the ends of the roll E and coaxially with said roll.

G, G, are set screws passing through holes in the upright side of the frame A, A, and provided with screw-threads engaging threads in said holes. The inner ends of the set-screws G, G, are hollowed out at g, g.

d, indicates apertures in the tracker board through which the air is drawn to operate the keys.

f, indicates the apertures in the music sheet which should register with the apertures in the tracker board.

My improvement is designed especially to be used with the form of instrument in which eighty-eight keys are operated and therefore the apertures d and f are made small in order that a large number may be got within the available space.

By adjusting the set screws G, G, the position of the roller E may be adjusted laterally. When the rollers are in operation the effect of the form of the roller E which enlarges from its ends toward its center, is to hold the music sheet accurately in position and out of contact with the flanges at the ends of the roller E.

What I claim is:—

1. The combination of a music roll, a tracker board having a plurality of apertures, a storage roll on the opposite side of the tracker board from the music roll, a guide roll interposed between the music roll and tracker board and so positioned as to give a tension to a sheet passing from the music roll over the tracker board, the said guide roll having a progressively increased diameter from the ends to the mid point, a perforated music sheet stored on the music roll passed under tension, across the guide roll, the tracker board and on to the storage roll, and means for adjusting the guide roll longitudinally of its axis, so as to line up the perforations on the music sheet with the apertures on the tracker board, substantially as described.

2. The combination of a music roll, a tracker board having a plurality of apertures, a storage roll on the opposite side of the tracker board from the music roll, a guide roll between the music roll and the tracker board and so positioned as to give tension to the sheet passing from the music roll across the guide roll, the said guide roll having flanges on its ends spaced from each other somewhat farther than the width of the sheet intended to be guided, and also having a greater diameter near its center and tapering toward the flanges, a music sheet stored on the music roll passed under tension across the guide roll, tracker board, and on to the storage guide roll, and means for adjusting the entire roll longitudinally of its axis, whereby the guiding means, capable of accommodating music sheets of different widths, is adapted to line the perforation therein up with the apertures on the tracker board by simply adjusting the guide roll, and to guide the music

sheet without injury to its edges, substantially as described.

3. The combination of a frame work, a music roll; a tracker board having a plurality of apertures, a storage roll on the opposite side of the tracker board from the music roll, a guide roll provided with pintles at its ends, disposed between the music roll and tracker board and of progressively increasing diameter from the ends to the midpoint, thereby adapted to accommodate sheets of varying width without adjustment therefor, a perforated music sheet stored on the music roll passing across the guide roll, tracker board, and on to the storage roll, and

set screws engaging in the frame work in alignment with the axis of the guide roll provided with hollowed inner ends adapted to act as bearings for the pintles of the guide roll, whereby music sheets of varying width ²⁰ may be properly lined up with the tracker board by adjustment of the set screws in the frame work, substantially as described.

In testimony whereof, I sign this specification in the presence of two witnesses.

JOSEPH COURVILLE.
